UNITED STATES PATENT OFFICE.

HARRY L. BERBERICH, OF HOLLISTER, CALIFORNIA.

PRUNE PICKER.

Application filed September 23, 1922. Serial No. 590,168.

To all whom it may concern:

Be it known that I, HARRY L. BERBERICH, a citizen of the United States, and a resident of Hollister, county of San Benito, State of California, have invented a new and useful Prune Picker, of which the following is a specification.

The present invention relates to improvements in tools designed to facilitate the picking up of prunes or the like. Referring to prunes particularly it is customary to allow the prunes to drop from the trees when they reach a certain stage of maturity and to pick them up from the ground. In an orchard of large dimensions it takes considerable time and a large crew of men to pick the prunes by hand and I propose to provide a device in the present invention that will greatly facilitate the picking of the prunes, allowing quite a number of them to be picked up simultaneously and dropped into a box or bucket.

With these objects in mind I have shown the preferred form of my invention in the accompanying drawing in which Figure 1 shows a top plan view of my implement, Figure 2 a vertical section through the same and Figure 3 a detail view of a portion of the bottom member of the frame used in my device. While I have shown only the preferred form of the invention it should be understood that various changes or modifications may be made within the scope of the claims hereto attached without departing from the spirit of the invention.

The frame (1) of my prune picking device comprises a plate (2) shown in plan view in Figure 3 of open construction so as to allow the operator to look through the same and provided with a plurality of perforations (3) and the handle (4) supported in spaced relation to the plate (2) by any suitable means as by the spacing members (6). A second plate (7) of substantially the same outlines as the frame plate and of similar open construction is disposed within the frame and normally forced into contact with the frame plate by means of a spring (8) pressing on the handle (9) for the second plate. The latter plate is provided with a plurality of downwardly extending pins (11) disposed so as to register with the various perforations (3) in the frame plate. It will be seen that in their normal position the pins extend through the frame plate and are adapted to engage a plurality of prunes

lying scattered on the ground when brought in contact with the same. The pins pierce the prunes sufficiently far to hold the same when the instrument is lifted. This piercing does not harm the prunes since in the ordinary drying process the prunes are usually guided over a rocking board provided with needles for breaking up the skin and thereby assisting the drying process. The operator after having lifted a number of prunes by means of the device lifts the same over a box or bucket or other receptacle and pulls on the handle (9) against the resistance of the spring (8) which causes the plate (7) to be lifted relative to the frame plate and the pins to be withdrawn during which operation the prunes are pushed from the pins by the frame plate (2). Stops (14) provided in the spacing member (6) limit the upward motion of the pin holding plate.

I claim:

1. In an implement for picking prunes or the like, a frame comprising a perforated plate having a handle supported in parallel and spaced relation thereto, a second plate between the handle and the first plate having a plurality of prune piercing elements thereon extending through the perforations in the frame plate, a spring bearing on the handle normally urging the plates together so as to cause the prune piercing elements to project beyond the frame plate, but allowing the second plate to be drawn away from the frame plate toward the handle whereby the prune piercing elements are withdrawn through the perforations.

2. In an implement for picking prunes or the like, a frame comprising a perforated plate having a handle supported in parallel and spaced relation thereto, a second plate between the handle and the first plate having a plurality of prune piercing elements thereon extending through the perforations in the frame plate and having a grip thereon formed for engagement with the fingers while the handle rests in the palm of the hand, a spring between the handle and the grip urging the plates together so as to cause the prune piercing elements to project beyond the frame plate, but allowing the second plate to be separated from the frame plate against the resistance of the spring whereby the prune piercing elements are withdrawn through the perforations.

HARRY L. BERBERICH,
